UNITED STATES PATENT OFFICE.

GEORG ALBERT GREEVEN, OF CREFELD, GERMANY.

APPARATUS FOR WASHING AND DYEING YARN.

SPECIFICATION forming part of Letters Patent No. 443,177, dated December 23, 1890.

Application filed July 20, 1889. Serial No. 318,138. (No model.) Patented in Belgium June 7, 1889, No. 86,561; in France June 7, 1889, No. 198,790; in Germany June 7, 1889, No. 49,718; in England June 7, 1889, No. 9,432; in Switzerland June 8, 1889, No. 1,099; in Italy June 30, 1889, XXIII, 25,731, and L, 448, and in Austria-Hungary October 24, 1889, No. 25,468 and No. 76,839.

To all whom it may concern:

Be it known that I, GEORG ALBERT GREEVEN, civil engineer, a subject of the King of Prussia, residing at Crefeld, Prussia, German Empire, 5 have invented certain new and useful Improvements in Apparatus for Impregnating, Washing, and Dyeing Yarn in Hanks or Skeins, (for which I have obtained Letters Patent in the following countries: in Belgium June 7, 10 1889, No. 86,561; in France June 7, 1889, No. 198,790; in Germany June 7, 1889, No. 49,718; in Great Britain June 7, 1889, No. 9,432; in Italy June 30, 1889, XXIII, 25,731, and L, 448; in Austria-Hungary October 24, 1889, No. 15 25,468 and No. 76,839, and in Switzerland June 8, 1889, No. 1,099;) and I do hereby declare the following to be a full, clear, and exact description of the invention, such as will enable others skilled in the art to which it appertains 20 to make and use the same, reference being had to the accompanying drawings, and to letters of reference marked thereon, which form a part of this specification.

Figure 1 is a vertical sectional elevation of 25 a washing or dyeing apparatus constructed according to my invention, and Fig. 2 is a section taken on line *x* *x* of Fig. 1.

In the washing or dyeing of yarn in the hank as heretofore effected the yarn was 30 suspended in the dye vat or beck so as to be immersed in the bath for about one half of its length, the parts being spread upon supporting-rods placed across the vat or beck, and were shifted to immerse the other half until 35 the operation of dyeing was completed, the dyed portion being alternately immersed into the dye-liquor and exposed to the action of the atmosphere. This operation requires time, and especially care, in order to obtain a 40 yarn uniformly dyed, and to prevent the yarn from tangling during the shifting of it the time occupied and the care required being much greater than when the yarn is passed through the dye-beck in an endless sheet or belt, in which latter case it is also difficult to 45 obtain a uniform depth of color.

The object of my invention is to provide a simple apparatus for dyeing yarn in the hank by the former method and whereby the labor 50 of shifting the yarn is done away with, (the

liquid itself being shifted,) and whereby at each immersion the whole of the hank will be immersed in the dye-liquor.

To these ends the invention consists in the combination, with the dye-beck, of means for supporting the hanks of yarn, a locking device to lock the supports against motion, and means for exhausting the dye-beck of its dye-liquor and returning the same thereto, substantially as hereinafter described, and as set forth in the claim.

In the drawings, A indicates the dye-beck, to the sides of which are secured racks *d* and *e*, that have notches or recesses *d'* *e'*, respectively, for the ends of the supporting-rods *b* for 60 hanks of yarn *a*.

f and *g* are locking-rails, that seat upon the racks *d* and *e*, respectively, to lock the rods *b* against vertical motion, yet the notches or recesses in the racks are preferably of such 70 depth as to admit of a slight rising-and-falling motion of the rods *b*. The said rails are locked to the racks by latches *h*, pivoted to the side walls of the dye-beck. The hanks of yarn are strung loosely on the rods, so that 75 on the inflow of the dye-liquor they will rise slightly with it, so that the threads thereof will become separated to afford access thereto of the dye-liquor.

Any suitable means may be employed for 80 alternately exhausting the dye-liquor from returning it to the dye-beck at a point proximate to the bottom thereof.

In the drawings I have shown an elevated reservoir *B* of such a capacity as to hold approximately 85 the entire charge of dye-liquor to be used in the beck A, said reservoir being connected by a pipe *c* with the said dye-beck near its bottom. The reservoir *B* is connected by a valved pipe *k* with any suitable air-exhaust 90 apparatus and is provided with an air-cock *l*.

The operation of this apparatus is as follows: The dye-beck A is first charged with the necessary amount of dye-liquor. A partial vacuum is then produced in the reservoir *B*, so 95 as to draw the dye-liquor into said reservoir. The rods *b* supplied with the hanks of yarn to be dyed are now locked in the dye-beck, as described, and the stop-cock *l* is opened to admit air to reservoir *B* and allow the dye- 100

liquor to flow back into the dye-beck, so that the hanks of yarn will be entirely immersed in the dye-liquor. After the hanks *a* have been exposed to the action of the dye-liquor 5 the stop-cock *l* is closed and that in pipe *k* opened, and a partial vacuum produced in reservoir B to draw the dye-liquor into the latter until the hanks are completely exposed to the action of the atmosphere, and this operation 10 is repeated until the hanks are properly dyed. As the dye-liquor rises in the dye-beck, the hanks float and are moved about more or less, thereby separating the yarn threads, and thus admitting the dye-liquor thereto; but 15 the hanks cannot rise with the dye-liquor by reason of their supporting-rods *b* being locked against such motion, there being one such rod at each end of the hank, and of course the latter cannot fall with the dye-liquor, but remains 20 suspended in the beck after said liquor has been introduced or withdrawn. Of course it will be understood that the means for introducing the dye-liquor into and exhausting the same from the dye-beck may be greatly varied. This may be done by means of a 25

pump or by air or steam pressure, and the reservoir B for the dye-liquor may in this case be located at any convenient point relatively to the dye-beck (even below the same) and the beck drained in it.

Having described my invention, what I claim, and desire to secure by Letters Patent, is—

The improvements in apparatus for dyeing yarn in the hank, which consists in the combination, with an open dye-beck and rods arranged in pairs one above the other for supporting hanks of yarn, said rods having a slight vertical play in the beck to allow the hanks to float in the dye-liquor, of a closed 35 reservoir, an air-valve for admitting air thereto, and means for exhausting the air from said reservoir, substantially as and for the purposes specified.

In testimony whereof I affix my signature in presence of two witnesses.

GEORG ALBERT GREEVEN.
